UNITED STATES PATENT OFFICE.

CLARENCE A. ROSS, OF JOLIET, ILLINOIS, ASSIGNOR OF ONE-HALF TO WILLIAM F. HORSTING, OF CHICAGO, ILLINOIS.

VOLUME AND PRICE RECORDER.

Application filed January 19, 1922. Serial No. 530,302.

This invention relates to a volume and price recording attachment for use on a machine for measuring and vending liquids.

It is an object of this invention to provide a liquid dispensing machine with a device adapted to punch, cut off and deliver a ticket from a roll of tickets in order that the volume of liquids delivered together with the exact price thereof will be definitely indicated by a punch mark on the issued ticket.

It is also an object of the invention to provide a liquid pumping machine with a ticket delivering mechanism which is so connected to coact with the pumping machine that a ticket cannot be punched and delivered unless liquid is actually pumped.

Another object of the invention is the construction of a ticket issuing recorder co-operatively mounted on a liquid pump to cause a punch mechanism to travel past a ticket by the motion of the pump operating mechanism to permit the ticket to be punched to indicate the volume and price of the liquid dispensed, to sever the punched ticket from the roll of tickets and to deliver the punched ticket from the machine by the operation of an auxiliary handle.

It is a further object of the invention to provide a liquid dispensing machine with a recorder having a moving punch mechanism adapted to be operated at the completion of a pumping operation to punch a ticket to correctly indicate the number of gallons of liquid dispensed, together with the total price thereof, depending upon the price per gallon at which the ticket is set.

It is furthermore an object of the invention to provide a recording device for an oil dispensing machine, said device having a roll of tickets, each ticket of which is printed to cover a plurality of prices per gallon of oil together with the total prices covering different quantities of oil.

It is an important object of this invention to provide an oil dispensing machine with a recording device having tickets adapted to be set to correspond to a given price per gallon of oil so that when a certain quantity of oil is dispensed an auxiliary handle is adapted to be operated whereby a traveling punch punches the ticket to indicate the total price of the oil dispensed at the set price per gallon, while a cutter mechanism cuts the

punched ticket from the roll of tickets and allows the severed ticket to drop by gravity through a discharge chute.

Other and further important objects of this invention will be apparent from the disclosures in the specification and the accompanying drawings.

The invention (in a preferred form) is illustrated in the drawings and hereinafter more fully described.

On the drawings:

Figure 1 is a front elevation of a liquid pumping machine equipped with a volume and price recorder embodying the principles of this invention.

Figure 2 is an end elevation of the recorder removed from the machine.

Figure 3 is an enlarged sectional view taken on line 3—3 of Figure 2, showing parts in elevation.

Figure 4 is a transverse section taken on line 4—4 of Figure 3, showing a portion of the ticket reel.

Figure 5 is a transverse section taken on line 5—5 of Figure 3.

Figure 6 is a transverse section taken on line 6—6 of Figure 3.

Figure 7 is a sectional view taken on line 7—7 of Figure 4.

Figure 8 is a section taken on line 8—8 of Figure 4.

Figure 9 is a fragmentary detail section taken on line 9—9 of Figure 7.

Figure 10 is a detail view taken on line 10—10 of Figure 3.

Figure 11 is a detail section taken on line 11—11 of Figure 4.

Figure 12 is a developed plan of the ticket roll showing one of the tickets punched.

As shown on the drawings:

The reference numeral 1 indicates a gaso-line or oil pump adapted to be operated in the usual manner by means of a crank 2. The crank 2 is attached to and operates a spindle 3 (Fig. 7) having a pinion 4 secured thereon and meshing with a rack bar 5 by which the piston of the pump is operated. The spindle 3 which has secured on the end thereof a toothed clutch member 6 complementary to the toothed clutch hub 7 of a large gear 8, constitutes the operating means or actuator for the recording mechanism to be hereinafter described. The large gear 8 is positioned within a casing or auxiliary

- housing 9 and has the toothed hub thereof held in engagement with the clutch member 8 by a spring 8^a. A projecting wall 10 is disposed at right angles on the housing 9.
- 5 Attached to the projecting wall 10 is a main casing or housing 11 enclosing the ticket punching and cutting mechanisms. Meshing with the large gear 8 is a small gear or pinion 12, (Fig. 8) which is secured on one end of a worm or feed screw 13 positioned within the main housing 11 and projecting into the auxiliary housing 9. Pivotally mounted within the auxiliary housing 9 is a pawl 14 (Fig. 10) having a tooth or lug 15 projecting at right angles therefrom into the plane of the large gear 8. A spring 16 is engaged with the pawl 14 and acts to hold the same out of engagement with the large gear 8 and in contact with the periphery of a circular disk 17 having a notch 18 in the periphery thereof to receive the pawl.
- Journalled longitudinally within the housing 11 is an operating or driving shaft 19, one end of which projects out of the housing 11 and has a handle or crank 20. The other end of the shaft 19 projects into the auxiliary housing 9 and has the notched disk 17 secured thereon. Keyed on the shaft 19 adjacent the wall of the auxiliary housing 9 is a mutilated gear 21. Rigidly secured on each end of the shaft 19 is a disk 22 having a peripheral tooth 23 (Fig. 5). Also secured on the shaft 19 adjacent the inner sides of the disks 22 is a pair of disks 24, each having a peripheral tooth 25. Keyed or otherwise secured on the shaft 19 adjacent the inner sides of disks 24 is a pair of disks 26 (Fig. 4) each having a peripheral tooth 27.
- 40 Disposed longitudinally within the main housing 11 is a shaft 28, one end of which is journalled in the wall of the auxiliary housing 9, while the other end projects into an opening in the outer end wall of the main housing 11. Keyed on the inner end of the shaft 28 adjacent the auxiliary housing 9 is a Geneva or mutilated gear 29 which is disposed in the plane of the mutilated gear 21 to coact therewith. Rotatably engaged on the shaft 28 is a sleeve 30 having a pair of spaced friction feed rolls 31 formed thereon to coact with friction feed rolls 32 formed on a ticket feed shaft 33. The shaft 33 is journalled in brackets 34 and 35 formed on the wall 10. The bracket 35 is provided with an opening in which the outer end of the sleeve 30 is rotatably engaged. The end of the sleeve 30 projecting through the bracket 35 is provided with clutch teeth 36 with which the clutch teeth 37 of a clutch member 38 interlock. The clutch member 38 is keyed on the outer end of the shaft 28, as shown in Figure 9, and holds the sleeve 30 locked with the shaft 28. The clutch member 38 is engaged in the opening in the

end wall of the housing 11 and is covered by means of the long arm 39 of a bell crank plate. The bell crank plate is pivoted by means of a screw 40 on the outer surface of the end wall of the housing 11. The short arm 41 of the bell crank plate abuts against a stop lug 42 formed on the housing 11. To hold the bell crank plate locked in place against rotation, a key-operated lock 43 is mounted on the back of the housing 11 so that the latch bolt 44 of said lock may be projected across the plane of the short bell crank 41, as illustrated in Figure 2.

Rotatably engaged on the sleeve 30 adjacent the bracket 35 and the mutilated gear 29 is a pair of spaced hook-shaped arms 45 having teeth or lugs 46 integrally formed thereon for co-action with the teeth 23 of the disks 22. The lower ends of the hook arms 45 contact with the end portions of a cutter bar 47, as illustrated in Fig. 11. The cutter bar 47 has the ends thereof slidably engaged in horizontal recesses 48 (Fig. 5) provided in supporting blocks 49 secured in the lower rear corners of the housing 11. Springs 50 are seated in recesses in the blocks 49 and engage the ends of the cutter bar 47, to hold the same in release position against the lower ends of the hook arms 45. As shown in Fig. 8, supported in notched portions of the blocks 49 are the ends of two parallel punch block guide bars 51 which are separated by spacer blocks 52 to afford a ticket slot 54 therebetween. Bolts 53 hold the guide bars 51 secured in place.

Rotatably engaged on the sleeve 30 adjacent the hook arms 45 is a pair of spaced bell crank members each comprising a short arm 54 and a long arm 55. The short arms 54 of the bell crank members are positioned in the plane of the disks 24 to be acted upon by the teeth 25 to throw the short bell crank arms 54 rearwardly and the long bell crank arms 55 outwardly. The feed screw 13 is supported by the long bell crank arms 55 and is moved outwardly therewith.

As shown in Fig. 6, also rotatably mounted on the sleeve 30 adjacent the bell crank members 54-55 is a pair of spaced brackets or arms 56 having projections or teeth 57 integrally formed thereon for coaction with the teeth 27 of the disks 26. Integrally connected to the arms 56 are lugs or fingers 58 which project inwardly toward one another, as shown in Figure 3, and have secured thereto a horizontally disposed channel bar 59. Engaged around the sleeve 30 is a spring 60, one end of which is bent to engage the short arm 54 of one of the bell crank members 54-55, while the other end of said spring 60 engages one of the arms 56.

The device is provided with a traveling punch mechanism comprising a slidably punch pin 61 which is supported in a recessed punch block 62. A spring 63 is engaged

around the punch pin 61 and holds the same in retracted position projected against the channel bar 56. The punch block is slidably supported on the guide bars 51 and is provided with a punch passage 64 disposed at right angles to a ticket slot 65. The punch block is provided with a concave recess 66 having partial threads to permit the feed screw 13, when rotating, to advance the punch block. The punch block 62 is provided with an integral arm 67 (Fig. 3) having a projecting pin 68 to which one end of a coiled punch block return spring 69 is attached. The other end of the spring 69 is connected to the auxiliary housing 9.

Mounted within the housing 11 is a ticket guide chute 70 (Figs. 4 and 7) having openings in the walls thereof to permit the ticket feed rolls 31 and 32 to project therein. Attached to the bottom of the housing 11 around a ticket discharge opening 71 is a ticket discharge chute 72. Fastened on the outer surface of the wall 10 is a metal strap or bracket 73 affording an opening 74 for receiving the flange 75 secured to a reel supporting casing 76. The reel casing 76 is held secured in place by a set screw 80 and has a roll of printed tickets 77 rotatably supported therein. A pair of guide rolls 78 is mounted within the casing 76 between which the printed ribbon passes when leaving said casing through an outlet slot 79. The ribbon passes into a slot in the top of the housing 11 into the guide chute 70 and between the feed rolls 31 and 32 and between the guide bars 51 on which the block travels. The upper portion of the housing 11 is provided with a sight opening 81, through which a portion of the ribbon can be seen. An indicating arrow is placed on the housing 11 near the sight opening 81 to afford a guide for setting the ribbon.

As illustrated in Figure 12, the ribbon 77 is printed to cover a plurality of integral tickets each covering a plurality of different prices "A" per gallon of gasoline or other liquid, said prices, as shown, ranging from 18¢ to 23¢. The ticket is also printed to indicate the total prices "B" at a given rate per gallon for different quantities "C" of gasoline ranging from 1 to 15 gallons. The ribbon is set so that the particular price at which the gasoline is to be sold, for example 20¢, is positioned in the sight opening 81, as shown in Figure 3, to register with the indicating arrow. This setting positions the 20¢ section of the ticket within the housing 11 in position to register with the punch pin 61.

60 The operation is as follows:

As illustrated in Figure 1, the volume and price recorder of this invention is adapted to be attached to the frame of a gasoline pump 1 to receive a drive from the spindle 3 through the large gear 8 and the small gear

12. The ticket reel casing 76 is removably supported above the housing 11 and is held in place by means of the set screw 80 which engages against the supporting flange 75. The reel casing is provided with a removable cover to permit a roll of printed tickets 77 to be rotatably supported within the casing. The printed ticket ribbon is trained between the rolls 78 and passes out of the casing 76 through the outlet passage 79 and enters the top of the housing 11. The ribbon then passes downwardly through the guide chute 70 and is visible through the sight opening 81 shown in Figure 3. The ribbon passes between the feed rollers 31 and 32 and downwardly through the housing between the punch block guide bars 51 to the ticket discharge chute 72.

When gasoline is to be sold at a given price per gallon, say twenty cents, the ticket ribbon 77 is adapted to be properly set by retracting the latch bolt 44 of the key lock 43. The plate 39 is thus released and is swung downwardly to uncover the clutch member 38 (see Figures 7 and 9). The clutch member 38 is pulled off of the shaft 28, thereby permitting the sleeve to be rotated by means of any suitable type of tool. Rotation of the sleeve 30 causes the feed rollers 31 to move the ribbon until the required price twenty cents registers with the sight opening 81 and with the indicating arrow shown in Figure 3. This adjustment of the ribbon positions a ticket within the housing 11 so that the portion of said ticket bearing the figures corresponding to the twenty cent rate will be positioned in the plane of the punch pin 61. The clutch member 38 is now placed back in position and the shutter plate 39 is moved into closing position, as shown in Figure 2. The lock 43 is then operated by means of a key to project the latch bolt 44 to hold the shutter plate locked against movement between the stop lug 42 and the latch bolt 44.

To operate the pump 1 the crank 2 is rotated to elevate the pump rack bar 5 to cause the pump to pump gasoline from a storage tank. At the end of the upward stroke of the rack bar, the same is released to permit the same to drop back into normal position. The crank 2 is again rotated and the operation repeated until the required volume of gasoline has been pumped. With the rotation of the crank 2, the spindle 3 is rotated, thereby causing rotation of the large gear 8 and the small gear 12 on the feed screw 13. The feed screw 13 is thus rotated thereby for setting the punch in accordance with the quantity dispensed by advancing the punch block 62 across the ticket to a point indicating the number of gallons of gasoline discharged by the pump. With the advance of the punch block 62 the control spring 69 is tensioned.

The crank 20 is now rotated, thereby ro-

tating the shaft 19 and the notched disk 17 within the auxiliary housing 9. The pawl 14 is thus moved out of the notch 18 against the action of the spring 16 and tracks on the 5 periphery of the disk 17, at the same time having been moved into locking engagement with the teeth of the large gear 8 (see Figure 10), thereby locking said gear and the pump crank 2 against movement. Rotation 10 of the shaft 19 rotates the disks 26 causing the teeth 27 to ride over the teeth 57 of the arms 56, as illustrated in Figures 4 and 6. The arms 56 are thus swung downwardly whereby the channel 15 bar 59 is forced rearwardly thereby actuating the punch pin 61 to punch the ticket at a set position indicated by the punch hole "D" in Figure 12. The ticket is thus punched, thereby indicating the number 20 of gallons of gasoline delivered by the pump and the total cost of the same at a certain rate per gallon depending on the setting of the ticket. As shown in Figure 12, the punch hole indicates 9 gallons at a total cost 25 of \$1.80 at 20¢ per gallon.

The disks 24 are also rotated with the shaft 19 and immediately after the punching of the ticket the teeth 25 of said disks are brought into engagement with the teeth of 30 the short arms 54 of the bell crank members, thereby causing the long arms 55 of the bell crank members to swing outwardly carrying the feed screw 13 out of engagement with the punch block. As soon as the punch 35 block 62 is released by the feed screw, the tensioned spring 69 acts automatically to return the punch block back into its initial position shown in Figure 8. It will be evident from Figure 6 that the spring 60 acts 40 downwardly upon arms 54 when arms 55 are contacted downwardly by the teeth of disks 24 to return the feed screw back into engagement with the punch block ready for the next operation of the pump.

45 After the release of the punch block the teeth of the mutilated gear 21 are brought into mesh with the teeth of the mutilated gear 29, thereby causing rotation of the sleeve 30 and the feed rolls 31 formed thereon. The punched ticket is thus frictionally 50 fed downwardly by the action of the rolls 31 and the rolls 32 on the rotatable ticket feed shaft 33.

When the last teeth on the mutilated gears 55 move out of mesh the teeth 23 on the disks 22 move into engagement with the teeth 46 of the hook arms 45. Said arms 45 are thereby forced rearwardly pushing the cutting bar 47 rearwardly, thus cutting off the 60 punched ticket from the remainder of the ribbon. The punched ticket which has been cut off falls by gravity through the ticket discharge chute 72. The springs 50 act automatically to return the cutting bar 47 65 to release position after a cutting operation.

The punching operation, the release of the punch block and the cutting operation of the ticket all occur during one revolution of the recorder crank 20. At the completion of the revolution of the shaft 19, the notch 18 in 70 the disk 17 is again brought to a point whereby the spring 16 acts to return the pawl 14 to seated engagement in the disk notch 18, thereby unlocking the large gear 8 and the pump crank 2 for the next operation of the 75 pump. With the feeding of the punched ticket through the recorder the next ticket is moved into position ready to be punched with the next operation of the pump and recorder. 80

The ticket ribbon may be printed to take care of any series of prices per gallon and with the total prices for any desired range of gallons other than those shown on the ticket form illustrated in Figure 12. If 85 desired a duplicate ticket ribbon may be run through the recorder with the main ticket ribbon to permit a record to be kept by the operator of the pump.

When the large gear 8 is released by the 90 pawl 14, the crank 2 is permitted to be rotated in a reverse direction to lower the rack 5 and the pump piston. The spring controlled clutch members 6 and 7 permit lowering of the rack after a pumping operation. 95

I am aware that numerous details of construction may be varied through a wide range without departing from the principles of this invention, and I therefore do not purpose limiting the patent granted otherwise than necessitated by the prior art. 100

I claim as my invention:

1. In a liquid dispenser having pump actuating mechanism and a punch set thereby in accordance with the quantity dispensed, 105 a ticket web, manually actuated means for successively locking said mechanism and actuating said punch, for punching said ticket web.

2. In a liquid dispenser having pump actuating mechanism and a punch set thereby in accordance with the quantity dispensed, 110 a manually rotatable member, means actuated by said member for locking and maintaining said pump against actuation and a punch actuating device operated by said member after the locking of said pump.

3. In a liquid dispenser having pump actuating mechanism and a punch set thereby in accordance with the quantity dispensed, 115 a manually rotatable shaft, means actuated by said shaft for locking said pump, a punch actuating device, a punch releasing device, and means operated by said shaft for effecting the operation of said devices. 120

4. In a liquid dispenser comprising pump actuating mechanism and indexing mechanism set thereby in accordance with the quantity dispensed, 125 a manually operable member, means successively operated by said 130

member for actuating said indexing mechanism and returning the same to initial position.

5. In a liquid dispenser comprising pump actuating mechanism and indexing mechanism set thereby in accordance with the quantity dispensed, a ticket web over which said indexing mechanism is set, a manually actuatable shaft, means actuated by said 10 shaft for locking said pump, and operating said indexing mechanism and driving mechanism for said ticket web operatively connected to said shaft after the actuation of said indexing mechanism.

15. 6. In a liquid dispenser comprising pump actuating mechanism and a punch set thereby in accordance with the quantity dispensed, a ticket web with respect to which said punch is set, manually actuatable means 20 for disabling said pump and actuating said punch for indicating upon said ticket web the quantity dispensed, means for returning said punch to initial position and driving mechanism for said ticket web operatively 25 connected with said manually actuatable means after the actuation of said punch.

7. In a liquid dispenser comprising pump actuating mechanism and a punch set thereby in accordance with the quantity dispensed, a ticket web with respect to which said punch is set, manually operable means 30 for locking said pump actuating mechanism and operating said punch and driving mechanism for said ticket web connectable with 35 said manually operable means after the operation of said punch.

8. In a liquid dispenser comprising a pump actuating mechanism operably connected with an indexing device for setting the same in accordance with the quantity dispensed, a ticket web with respect to which said indexing mechanism is set, a manually operable shaft, means operated by said shaft for effecting engagement of said indexing 40 mechanism and ticket web and driving mechanism for said ticket web operably connected with said shaft after the indexing operation.

9. In a liquid dispenser comprising pump operating mechanism and an indexing mechanism set thereby in accordance with the 50

quantity dispensed, a ticket web with respect to which said indexing mechanism is set, manually operated means for locking said pump and actuating said indexed mechanism, and driving mechanism for said ticket web adapted to be connected with said means after the indexing operation. 55

10. In a liquid dispenser comprising pump actuating mechanism and an indexing mechanism set thereby in accordance with the quantity dispensed, a ticket web with respect to which said indexing mechanism is set, a manually rotatable shaft, means operated by said shaft for locking said pump actuating mechanism, and operating said indexing mechanism for marking said ticket web, means set in motion by the rotation of said shaft for returning said indexing mechanism to initial position and driving mechanism for said ticket web connectable with 60 said shaft after a partial revolution thereof. 65

11. In a liquid dispenser, dispensing mechanism, a ticket strip, a punching member, a connection between said punching member and said dispensing mechanism whereby said punching member is moved relative to the strip according to the quantity dispensed, a manually actuated member, and means actuated by said actuatable member for locking said dispensing mechanism and effecting engagement of said punching member and 70 ticket strip. 75

12. In a liquid dispenser, dispensing mechanism, a ticket strip, a punching member, a connection between said punching member and said dispensing mechanism whereby said punching member is set in accordance with the quantity dispensed, a manually actuatable shaft, locking mechanism actuated by said shaft for locking said dispensing mechanism, other mechanism actuated by said shaft for effecting engagement of said punching member and ticket strip, and a driving connection between said shaft and ticket member operable after the punching operation. 80 85 90 95

In testimony whereof I have hereunto subscribed my name.

CLARENCE A. ROSS.
